UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING-MACHINE.

1,377,446.

Specification of Letters Patent.

Patented May 10, 1921.

Application filed June 19, 1919. Serial No. 305,237.

To all whom it may concern:

Be it known that I, JESSE A. B. SMITH, a citizen of the United States, residing in Stamford, in the county of Fairfield and State of Connecticut, have invented certain new and useful Improvements in Type-writing-Machines, of which the following is a specification.

The present invention relates to book-keeping devices, and is herein disclosed as comprising the carriage of an Underwood standard bookkeeping machine. Such machines are frequently used for making entries on individual cards or memorandum sheets, and copies of such entries are often kept upon proof or record sheets, there usually being a single entry upon each memorandum sheet made at a time while the proof or record sheets are retained in the machine and all entries made thereon in sequence until the sheet is full.

According to the present invention, a simple device may be utilized for retaining the proof or record sheet in its adjusted position while a memorandum sheet or card is being inserted. This device may take the form of a chute which is adapted to receive the memorandum sheet and to bear against the surface of the proof sheet when the latter is passed around the platen, thereby retaining that sheet in place while the usual feed-rolls are cast off. To enable the proof sheet to be withdrawn, the chute may be swung to a position clear of the platen, thus relieving all pressure upon the proof sheet.

Other features and advantages will hereinafter appear.

In the accompanying drawings,

Figure 1 is a perspective view of an Underwood bookkeeping machine carriage, showing the present invention as applied thereto.

Fig. 2 is a sectional side view of the same, as adjusted when inserting a proof or record sheet.

Fig. 3 is a perspective view of a guide wire for guiding the inserted work-sheet adjacent the printing point.

Fig. 4 is a diagrammatic sectional side view, on a small scale, showing the carbon sheet as much longer than its associated proof or record sheet.

Fig. 5 is a sectional side view, similar to Fig. 2, but showing the chute in its normal

position and holding the proof or record sheet upon the platen.

Fig. 6 is a perspective view of a paper-finger.

Fig. 7 is a perspective view diagrammatically showing the relationship of entries upon the memorandum sheet and proof or record sheet.

Fig. 8 is a diagrammatic perspective view of the memorandum sheet as bent when around the platen.

The platen 1 is journaled by its axle 2 in the end plates 3 and 4 of the shift-frame which forms part of the carriage 5 and in which it is adapted to be rotated by the usual line-space wheel 6 at the actuation of the usual handle 7. To insert the proof or record sheet 8, it is joined at the leading end, by means of clips 9, to a carbon sheet 10, of the width of a memorandum sheet 11 which will be later described. The carbon sheet 10 and proof sheet 8 are passed together down the usual paper-table 12, between the usual adjustable edge gages 13, to the rear feed-roll 14 from which they pass forwardly and upwardly past the front feed-roll 15 to the printing point at the type-guide 16. Before reaching the printing-line, the leading edge 17 may engage paper-fingers 18, which extend down almost to the feed-rolls 15, and which are formed as lower extensions of brackets 19 slidable upon a transverse rod 20. To hold the fingers 18 yieldingly and slidably in place, the brackets 19 each support a spring 21, which presses a rounded key 22, connected to the brackets into the spline 23 of the rod 20. The fingers 18 are adapted to overlie the margins of the proof sheet 8, and include directing plates 24 which extend down near the platen and serve to guide the advancing or leading edge 17 upwardly over the rod 20.

To insert the memorandum sheet 11, a chute 25 is adapted to normally rest its toes 26 with some pressure upon the surface of the proof sheet 8 as it lies upon the platen. The chute by this pressure holds the proof sheet 8 against sliding on the platen, thus permitting the feed-rolls 14 and 15 to be cast off by actuating the usual casting-off handle 27. Then the typist lifts the extension 28 of the bottom of the carbon sheet 10 which is long enough to always lie at a convenient point upon the paper-

table 12 to be lifted when the printing line is upon the proof sheet. The typist then inserts behind it the memorandum sheet 11, sliding the latter down over the paper-table 5 12 and over the feed-rolls 14 and 15 and up onto the top of the chute between the springy margins which are formed as turned-up edges 29 thereof. Then the typist may actuate the handle 27 to cast on the 10 feed-rolls, thus clamping both sheets against the platen. The memorandum sheet is then ready to be written upon.

If the item is the last item shown upon the sheet shown, the typist, in pursuing the 15 usual course, first copies out the previously shown balance, which will be the one shown under date of March 10, namely, \$2115.25, copying it in the pick-up column 30 of the proof sheet 8 and thereby adding it in the 20 computing register of the kind often found in Underwood bookkeeping machines, one form of which is disclosed in the patent to Hoyt No. 1,280,228. Then the typist brings the carriage to write the account number 25 and the name of the account upon the left-hand margin of the proof sheet 8, and then writes the date and the amount in the date and deposits - columns 32 and 33 of the memorandum sheet. In entering the amount 30 in the deposits-column, the typist adds that amount in the register above mentioned. Next the typist sets the machine to write in the balance-column 34 and copies therein the balance now shown in the register, namely, 35 \$2125.25, subtracting it out. Then the typist prints the usual star to prove the accuracy of the copying.

Usually only one entry at a time is made 40 in a memorandum sheet, so the next step 40 is to remove the memorandum sheet from the machine by first releasing the feed-rolls and then removing the sheet from the machine. In order to prevent the ribbon 35 and its vibrator from being entangled or 45 caught by the memorandum sheet 11, there is provided a wire guide having offset feet adapted to fit in openings 38 in the base of the type-guide and having wings 39 at each side of the U-top 40 which joins the two 50 legs 37, said wings being flared outwardly and being stiff enough to deflect the memorandum sheet 11 when in position. As here- 55 in illustrated, the memorandum sheet is in the form of a card of considerable stiffness, and it advantageously fits so closely between the resilient springy sides 29 of the chute 25 that it is retained in position even if at the very top of the front feed-roll 15. If the chute 25 is made of light and resilient 60 enough metal, the edges or sides 29 will be springy enough to serve the purpose if they are simply bent up from the body of the chute and incline slightly outwardly. In order to enable the chute 25 to be swung 65 clear of the platen, to facilitate the insertion

of the proof sheet 8 and its carbon 10, a finger-piece 41 may be pushed rearwardly, thus turning a shaft 42, to which it is fast, so that the chute 25, which is, so to speak, journaled on the shaft by ears 43, will be 70 lifted from the platen. The shaft 42 turns so stiffly in the brackets 44, in which it is mounted upon the ends 3 and 4, that it stays wherever set. When the finger-piece 41 is moved backwardly, the toe 26 of the chute 75 stands clear of the platen, as shown in Fig. 2, and the proof sheet may be easily inserted. When the proof sheet has been inserted and properly centered, the chute 25 is moved back against the platen by pulling 80 the finger-piece 41 forward.

In order to hold the chute 25 against the platen with some resilience, there is provided a kerf 45 in the shaft 42, in which rests a rounded key 46, which is pressed into 85 the kerf 45 by a spring or springs 46^a between the ears 43. The key 46 yields enough to give considerable spring to the chute 25 as it rides upon the platen, thus giving the requisite pressure without hindering the 90 turning of the platen. In order to prevent the proof sheet 8 from catching its leading edge in the rod or shaft 42, there is provided beneath the chute 25 a deflector plate 48 for camming downwardly the leading 95 edge of the proof sheet 8, said plate extending from near the toe 26 of the chute rearwardly under the shaft 42, thus enabling the typist to be assured that the proof sheet 8 will take care of itself when once inserted 100 properly, even if it is so wide that it bellies out away from the platen at its center.

It will usually be found most convenient for the typist to insert the card 11, bringing the desired line thereon to the printing 105 point. After making the desired entries, the typist will usually verify the work, subconsciously actuating the line-space lever 7, and then remove the card, thus leaving the proof sheet 8 in position for the next 110 entry.

In order to give added resistance to accidental turning of the shaft 42, it may be frictionally held by a spring 49, supported against it by a small bracket 50 fast to one 115 of the brackets 44.

Variations may be resorted to within the scope of the invention, and portions of the improvements may be used without others.

Having thus described my invention, I 120 claim:

1. In a front-strike typewriting machine, the combination with a revoluble platen and a rear paper-table, of releasable feed-rolls for holding work-sheets against the platen, 125 a chute in front of the platen and normally clear of it, paper-fingers adapted to guide a wide work-sheet behind the chute, and means for swinging the lower edge of said chute against the platen to bind the wide 130

- work-sheet while a narrower sheet is being passed around the platen and onto the chute.
2. In a typewriting machine, the combination with a revoluble platen, of means including a paper-table to present to the platen a record-sheet and a longer carbon-sheet connected together at their leading ends, releasable devices for holding work-sheets in operative relation with respect to the platen 10 to be line-spaced therewith, means for holding a second sheet and detaining the record-sheet when said devices are released, so that upon grasping and lifting the portion of the carbon sheet extending beyond the end of the record-sheet, said portion may assist in 15 guiding the second sheet around the outside of the record sheet, and means for rendering the holding and detaining means ineffective.
3. In a front-strike typewriting machine, 20 the combination with a revoluble platen, of means, including a rear paper-table, to present to the platen a record-sheet and a longer carbon-sheet having their leading edges connected together, means for holding a second sheet and for detaining the record-sheet, releasable feed-rolls to coöperate with the platen, the portion of said carbon-sheet extending beyond the end of said record-sheet being adapted to guide the second sheet 25 around the outside of the record sheet, and means releasing the holding and detaining means.
4. In a typewriting machine a revoluble platen a rear paper table to present to the 30 platen a record sheet and a carbon sheet, means for gaging and guiding the forward ends of the record and carbon sheets, means for gaging and holding a second sheet and means intermediate the two gaging and 35 guiding means to prevent the record and carbon sheets from interference with the second gaging and guiding means.
5. In a typewriting machine a revoluble platen, means to guide to the platen a record 40 and a carbon sheet extending rearwardly of the record sheet, means for fastening together the front ends of said sheets and a tilttable chute for guiding a second sheet from the platen.
6. In a front-strike typewriting machine, 45 the combination with a revoluble platen, of a chute above and in front of the platen, and means for swinging the lower edge of the chute against the platen to bind a work-sheet 50 against the platen while a second work-sheet is passed around the platen onto the chute.
7. In a front-strike typewriting machine, 55 the combination with a revoluble platen, of a chute above and in front of the platen, a rod on which said chute is mounted, and means for rotating said rod to swing the chute against the platen, from its position 60 normally clear of the platen, to cause it to yieldingly bind a work-sheet against the platen, and to remain in said position.

8. In a front-strike typewriting machine, the combination with a revoluble platen, of a chute above and in front of the platen, a rod on which said chute is mounted, means for rotating said rod to swing the chute 70 against the platen, from its position normally clear of the platen, to cause it to yieldingly bind a work-sheet against the platen, and to remain in said position, and a deflector beneath the chute to guide beneath the rod a work-sheet carried underneath the chute.

9. In a front-strike typewriting machine, the combination with a revoluble platen, of a chute above and in front of the platen, a rod on which said chute is journaled, a connection between the chute and rod tending to make the chute turn with the rod, and a mounting for the rod adapted to permit it to be turned to different settings to effect 85 corresponding settings of the chute and to hold said rod where set.

10. In a front-strike typewriting machine, the combination with a revoluble platen and a rear paper-table, of a chute above and at 90 the front of the platen and adapted to gage the sides of a work-sheet passed around the platen, a side gage for another sheet upon the paper-table, feed-rolls for advancing the work-sheets, means for casting off said feed-rolls to remove and insert a sheet, and means for detaining the second sheet while the first 95 is being removed.

11. In a typewriting machine a revoluble platen, a rear paper table to present to the 100 platen a record sheet and a carbon sheet extending rearwardly back of the record sheet, means for fastening together the front ends of the record and carbon sheets, a chute for holding a second sheet and guiding means to 105 prevent the forward ends of the record and carbon sheets from interference with said chute.

12. In a front-strike typewriting machine, the combination with a revoluble platen, of 110 a chute above and in front of the platen, a rod on which said chute is journaled, a connection between the chute and rod tending to make the chute turn with the rod, a mounting for the rod adapted to hold it 115 where set, a toe on the chute adapted to retain a work-sheet upon the platen, an edge gage for the work-sheet, and feed rolls for advancing another work-sheet in the chute together with the first-named work-sheet. 120

13. In a front-strike typewriting machine, the combination with a revoluble platen, of a chute above and in front of the platen, a platen frame, a rod in said frame on which the chute is journaled, a kerf in said rod, a 125 key tending to carry the chute with the turning rod, and means to turn said rod to swing said chute into and out of contact with said platen.

14. In a front-strike typewriting machine, 130

the combination with a revoluble platen, of
a chute above and in front of the platen, a
rod on which said chute is journaled, ears
beneath the chute by which it bears on the
5 rod, a connection between the chute and rod,
tending to make the chute turn with the rod,
a mounting for the rod adapted to hold it

where set, and a deflector beneath the chute
to guide a work-sheet clear of the rod.
